(57) **CLAIM**

The ornamental design for the ovalish dispensing closure, as shown and described.

DESCRIPTION

FIG. 1 shows a top, front perspective view of an ovalish dispensing closure;

FIG. 2 shows a top plan view of the ovalish dispensing closure;

FIG. 3 shows a left sided view of the ovalish dispensing closure;

FIG. 4 shows a front plan view of the ovalish dispensing closure;

The rear side plan view would be a mere image of the front plan view;

FIG. 5 is a right sided view of the ovalish dispensing closure; and,

FIG. 6 is a left sided view of the ovalish dispensing closure.
